MOLDED BATHING CAP

Irving Neustadter, 246 Bay 19th St., Brooklyn, N.Y.

Filed Apr. 20, 1961, Ser. No. 104,436

1 Claim. (Cl. 2—68)

This invention relates to bathing caps, more especially to bathing caps for women and girls.

Bathing caps as now manufactured have certain inherent serious disadvantages due to the fact that they are supposed to have a tolerable water-tight fit on the wearer's head and yet be salable to and usable by individuals of various head sizes and shapes. The disadvantages are aggravated in the case of bathing caps which are made in a single size but are marked and sold "to fit all sizes." One well known disadvantages is that even when the caps are made in two or more sizes, it is difficult if not impossible for many women to obtain bathing caps which answer their requirements as to head sizes and shapes. Another serious disadvantage is that the bathing caps may and frequently do disarray or even spoil the wearers' hairdos, often because of the close engagement of the cap with the top, sides and back of the head and the resulting excessive pressure of the cap on the hair.

The primary object of the present invention is to obviate the above mentioned disadvantages and for that purpose to provide a bathing cap which is so made that it is better adapted to conform to the size and shape of the wearer's head and can be worn without seriously impairing the wearer's hairdo.

The above and other objects, features and advantages of the invention will be more fully understood from the following description considered in connection with the accompanying drawings which are illustrative of the presently preferred embodiment of the invention.

In the drawings:

FIG. 1 is a side view of a bathing cap according to the present invention;

FIG. 2 is a rear view of the bathing cap;

FIG. 3 is an enlarged view of a portion of the bathing cap encircled in FIG. 1;

FIG. 4 is a cross sectional view, on a larger scale, taken on line 4—4 of FIG. 1;

FIG. 5 is a cross sectional view, similar to FIG. 4, but showing the pleated material in an expanded condition; and

FIG. 6 is a cross sectional view, on a larger scale, taken on line 6—6 of FIG. 1.

Referring now to the drawings in detail, the bathing cap 10 is formed of rubber or any other suitable elastomer and comprises the head-enclosing part 12, having an outer edge 14 and the usual chin strap 16 which is secured to portions 18 at the lower ends of edge 14. The lower edge 20 of the cap defines the usual neck opening of the cap. A water seal 22 comprising a pair of spaced ribs 24 extends along the inner surface of edge 20 and along the inner surface of the lower portions of edge 14 at each side of the cap. Said water seal may be of any other suitable type.

In accordance with the present invention and pursuant to the primary object thereof, the head-enclosing part 12 consists essentially of a single layer of the elastomer material and is not only molded to head-contour but is pleat-molded substantially throughout its contour to provide said part with a multiplicity of molded pleats 26. More particularly, the pleats are molded into the cap during the molding thereof to the desired head contour and head size and they are molded and set into the desired longitudinal and transverse or cross sectional contours simultaneously with the molding and setting of the cap to the head contour by vulcanization of the elastomer in its shaped

2

condition in the mold. The pleats 26 are V-shaped in cross section and are easily expandable and contractable in accordian-like fashion so that the cap is to a large extent self adjustable to the contour and size of the wearer's head within a range of head sizes. The self size-adjustability of the cap due to its molded pleated configuration not only makes it possible to reduce the number of caps of different head sizes heretofore required to be made by the manufacturer but also results in the important advantage of minimum or no disturbance of the wearer's hairdo.

FIG. 4 shows the material of the head-enclosing portion 12 of the cap in an unexpanded, off the head condition. In FIG. 5 there is shown the same part of the material of FIG. 4, but in an expanded condition when the cap is worn. In this expanded condition it will be noted that the increase in size of the parts of the head-enclosing portion of the cap occurs because of the expansion of the pleats and does not occur due to any stretchability of the material but, on the contrary, in its expanded condition the material is stretched very little if at all. The thickness of the material and depth of the V-shaped pleats can vary over a considerable range. For example, but without limitation, the thickness of the material may be in the order of .020 to .025 inch and the depth of the pleats can be about one-eighth of an inch. It will be understood that the cap is contour-molded and pleat-molded by the use of companion male and female grooved parts to provide the pleats of the longitudinal and cross sectional contours above and hereafter indicated.

As illustrated here, the pleats 26 of the crown part 28 of the cap extend horizontally from one side of the cap to the other side and are parallel to each other, and the back 30 of the cap also has pleats which extend horizontally from one side of the cap to the other and are parallel to each other. This is the preferred form of the cap because the horizontally extending pleats at the crown and back of the cap facilitates its molding since a two part mold is employed and the mold parts are movable horizontally toward and away from each other for the molding operation.

The sides 32 of the bathing cap are identical and are provided with pleats 26 which are arranged to resemble a woman's hairdo in order to provide a pleasing appearance for the cap and at the same time permit expansion of the cap along the sides of the wearer's head to conform to the configuration of the underlying hairdo. Due to the particular configuration illustrated it will be understood, as best seen in FIG. 3, that the pleats in cross-section do not always resemble a perfect V but vary in shape, as illustrated, due to the direction of flow of the lines which form the pleats. Where the pleats are straight, such as at the crown and back of the cap, the pleats resemble a perfect V in cross section but where they extend along curved lines the V form is modified in the manner illustrated in FIG. 3 but accomplish their function since they are expandable and expand to conform to the part of the person's head which they confront and, in addition, provide the pleasing appearance heretofore referred to.

While I have shown and described the preferred embodiment of my invention, it will be understood that the invention may be embodied otherwise than as herein specifically illustrated or described, and that certain changes in the form and arrangement of parts and in the specific manner of practicing the invention may be made without departing from the underlying idea or principles of this invention within the scope of the appended claim.

What I claim is:

70 A molded bathing cap having a head enclosing portion comprising a single layer of resiliently elastic material, said layer of material having parts for covering the crown,

sides, and back of the wearer's head, said crown part and said back part of said head enclosing portion each having a series of molded pleats of substantially uniform thickness extending from one side to the other side of said head enclosing portion, said crown and back pleats being parallel to each other, and said side parts of said head enclosing portion having a series of molded pleats of substantially uniform thickness, said pleats in said parts being collectively arranged in a configuration resembling a woman's hairdo, said pleats being expandable so that said

head enclosing portion can increase in size and conform to the shape of the wearer's hairdo.
